UNITED STATES PATENT OFFICE.

RAYMOND S. LOWER, OF GENESEO, ILLINOIS.

EGG BEATER.

1,425,026.

Specification of Letters Patent. Patented Aug. 8, 1922.

Application filed November 9, 1921. Serial No. 513,969.

To all whom it may concern:

Be it known that I, RAYMOND S. LOWER, a citizen of the United States, residing at Geneseo, in the county of Henry and State 5 of Illinois, have invented a new and useful Egg Beater, of which the following is a specification.

This invention relates to egg beaters, and aims to provide novel means for operating 10 the beating arm to facilitate the egg beating operation.

Another object of the invention is to provide a device of this character which will give a combined vertical and reciprocatory 15 movement to the beater head, by a single operation of the operating handle.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 20 within the scope of what is claimed, without departing from the spirit of the invention.

Referring to the drawing:

Figure 1 is a side elevational view of an 30 egg beater constructed in accordance with the present invention.

Figure 2 is a plan view of the same.

Figure 3 is a sectional view on line 3—3 of Figure 1.

Figure 4 is a sectional view on line 4—4 of Figure 1.

Figure 5 is an enlarged detail view disclosing the operating disk in section to illustrate the connection between the disk and 40 operating arm.

Referring to the drawing in detail, the reference character 5 designates the base or support of the beater, which has an upwardly extending supporting bar 6 secured 45 adjacent to one end thereof.

Secured to the base, at a point intermediate its ends, is a bracket member 7 which has pivotal connection with the base 5 as through the pivot pin 8, as clearly shown by Figure 50 3 of the drawing, and which extends upwardly in the bracket member 7. The upper end of the bracket member 7 is cut away to provide opposed arms 9 between which the operating arm 10 is pivotally supported,

there being provided a pin 11 as connecting 55 the arms 9 and 10 to permit the arm 10 to rock on the bracket.

Mounted on the supporting bar 6 is a gear wheel 12 which is operated by means of the handle 13 and which is in mesh with the 60 pinion 14 mounted above the gear wheel 12. This pinion 14 is secured to the shaft 15 that extends through the supporting bar 6 whereby rotary movement of the pinion 14 is imparted to the shaft, which in turn imparts 65 rotary movement to the operating disk 16 keyed, or otherwise secured to the shaft 15.

Formed in the operating disk 16 is an elongated opening 17 which is disposed eccentrically thereof and is designed to accommodate bolt 21 which is formed with a head 22 and a threaded extremity 23. The threaded extremity 23 is positioned in a threaded opening in the head 24 which is formed with a socket to accommodate the 70 ball 25 formed integral with one end of the rod 18, which rod moves in a bore formed in one end of the operating arm 10 as clearly shown by Figure 1 of the drawing. From the foregoing it will be seen that due to this 75 construction, the bolt may be moved to various positions, within the slot 17 to change the point of connection between the rod 18 and disk 16, to vary the stroke of the operating arm 10 and adopt the same for use in 80 connection with containers of various sizes. The beater head is indicated at 19 and includes an arm 20 curved and connected to the arm 10, as at 21'.

In the use of the device, a bowl or similar container as shown in dotted lines is positioned under the beating head 19 and the material to be beaten, is placed therein. The handle 13 is now operated to cause the operation of the arm 10 as described, whereupon the beating operation is accomplished 95 with facility.

Having thus described the invention, what is claimed as new is:—

In a device of the character described, a 100 base, a supporting bar on the base, gears carried by the supporting bar, an arm having a bore formed in one end thereof and pivotally supported above the base, a disk supported at one end of the base and having an 105 elongated opening formed eccentrically thereof, a bolt extending through the opening, a head formed with a socket carried

by the bolt and adapted to be secured within the elongated opening in various positions of adjustment, a rod having a head positioned in the socket, said rod adapted to move in the bore of the first mentioned rod, and gearing for rotating the disk.

In testimony that I claim the foregoing as

my own, I have hereto affixed my signature in the presence of two witnesses.

RAYMOND S. LOWER.
